UNITED STATES PATENT OFFICE

2,625,019

DRINKING CUP

Abner E. Brown, Richmond Heights, Mo.

Application September 20, 1947, Serial No. 775,207

5 Claims. (Cl. 65—13)

1

The present invention relates to feeding utensils for babies and more particularly to a drinking cup of the so-called "slow-flow" type, wherein the flow of milk, water, or other liquids is restricted when the cup is tilted in use. The arrangement is such that the cup cannot deliver liquid at a rate greater than the capacity of the child to consume it, regardless of the amount of tilting of the cup. Also, spilling of the entire contents following fortuitous upsetting of the cup is obviated.

The principal object of the invention, therefore, is to provide a cup of simple construction including an insertable and removable flow regulating member, and including means to retain said member in position at a predetermined elevation below the peripheral upper edge of the cup.

Another object is to provide means on the flow regulating member to facilitate its insertion into and removal from the cup body.

Other advantages will be apparent from the description to follow, reference being had to the accompanying drawing, in which:

Fig. 1 is a top plan view of a drinking cup embodying the present invention;

Fig. 2 is a vertical sectional view taken on the line 2—2 of Fig. 1;

Fig. 3 is a similar view taken on the line 3—3 of Fig. 1;

Fig. 4 is a view similar to Fig. 2 illustrating the manner in which the flow regulating member is manually flexed while being inserted or withdrawn;

Fig. 5 is a view similar to Fig. 2 illustrating a slight modification; and

Fig. 6 is a top plan view of an insert ring utilized in the Fig. 5 modification.

With particular reference now to Figs. 1 to 4, inclusive, the drinking cup of this invention is generally designated 10. It includes a bottom wall 11, a cylindrical vertical wall 12 terminating in a beaded upper peripheral edge or rim 13. A conventional handle 14 is provided.

Rigidly secured in any suitable manner to the inner peripheral surface of the wall 12 are opposite groups of lugs or equivalent means suitably shaped for the purpose to appear. In the preferred illustrated form, there is a first pair of diametrically opposite lugs or abutments 15 provided with flat lower surfaces 16, as best seen in Fig. 4. In like manner, there is a second pair of diametrically opposite lugs 17, these lugs having flat upper surfaces 18 also best seen in Fig. 4. As apparent from an inspection of the drawing, the horizontal plane of the flat surfaces 18 is

2

preferably slightly lower than that of the flat surfaces 16. And, as shown in Fig. 1, the lugs are spaced ninety degrees apart, in the preferred form.

As shown in Figs. 2 and 3, a thin resilient disc or metal wafer 19, the diameter of which is slightly less than the internal diameter of the wall 12, is removably maintained in position in the cup by the cooperation of the lugs 15 and 17, and provides a very narrow annular opening 20 between its peripheral edge and the internal face of the wall 12.

As will appear, the disc is insertable and removable from the cup by a flexing operation. Means whereby manual flexing or bowing of the disc 19 is facilitated are provided. As illustrated in Fig. 3, an inverted U-shaped bail, generally designated 21, may be employed for this purpose. The bail 21 includes legs 22 slidable in spaced openings 23 formed in the disc 19. Movement of the bail in one direction is limited by the bight 24 thereof, and in the opposite direction by a head, or the like, 25 formed on the extremity of each leg 22.

A slight modification is illustrated in Figs. 5 and 6 wherein the same reference characters are applied to parts that are similar. In the modified form, the lugs 15 and 17 are rigid with a ring member 30, which may be removably press fitted into the cup. This ring is provided with an annular upper beaded edge 31, serving to limit the downward movement of the ring and also to facilitate its withdrawal. By this arrangement, the flow control means hereof may be made as an accessory to the cup itself, requiring no structural changes or additions thereto. In the earlier form, the lugs are permanent parts of the cup, remaining after the child has outgrown the need of the flow control. However small these lugs are relatively to other analogous means, they are eliminated by the arrangement of Figs. 5 and 6.

In use, assuming that the cup has been filled with a liquid to an optional level below the lugs 17, such as that indicated by the reference character x in Fig. 2, the flow restricting disc 19 is flexed or bowed by the use of the index finger and thumb, as illustrated in Fig. 4. This contracts the distance between the opposite edges of the disc to less than that between the opposite lugs 15 without reducing the distance at ninety degrees thereto, or between the edges spanning the other lugs 17. With the disc thus flexed, it is lowered into the cup until the contracted edges are below the surfaces 16 of the lugs 15, or until the edges at ninety degrees thereto engage the

upper surfaces 18 of the lugs 17. Thereupon, manual pressure is gradually decreased until the member 19 snaps into the position shown in Figs. 2 and 3, and is retained there by its inherent resistance to flexing. Due to the flat surfaces provided on the lugs, the member 19 is thus firmly held in place regardless of the angular position of the cup, in the hands of the child or otherwise.

The restricted annular opening 20 affords a restricted rate of flow that will prevent the child from receiving liquid at rates greater than he can properly assimilate it. The cup will aid the child in learning to drink properly and will prevent the spilling of the entire contents should the cup be accidentally overturned. Also, its parts are so designed that complete removal of food particles or film can readily be made, and full sterilization is possible, as by boiling, without injury to the parts.

The openings 23 in the disc 19 permit the bail 21 to drop to the position shown in Fig. 3 when the element 19 is in place. Aside from appearance factors, this causes it to withdraw from a position wherein it might interfere with drinking from the cup.

While the preferred embodiment of the invention has been illustrated and described, it obviously may admit of slight modifications, such as the Fig. 5 embodiment, without departing from the spirit of the invention.

What is claimed is:

1. In a cup of the character described, means in the form of a flexible resilient member to regulate the flow of contents therefrom, spaced stop means rigid with the vertical wall of the cup to maintain said member in a predetermined plane within the cup, and a handle associated with said member to facilitate its insertion into and removal from the cup, said handle comprising a lateral bight portion on the outside of said resilient member, legs attached thereto slidably with respect to said resilient member, said legs being attached to heads on the side of the resilient member opposed to said bight portion of the handle, said heads acting as stop members and being movable to a position adjacent the resilient member, said handle facilitating the insertion and removal of the resilient member in the cup by serving as a fulcrum support when the edges of the resilient member are deflected.

2. In a cup of the character described, a removable thin resilient metallic member to restrict the flow of liquid, and means to maintain said member at a predetermined elevation relative to the upper peripheral edge of the cup, said means comprising a first set of diametrically opposed abutment members each having a flat bottom surface, and a second set of diametrically opposed abutment members each having a flat top surface, each of said abutment members being rigidly secured to the vertical wall of the cup interiorly thereof with the flat surfaces of each set parallel and located a predetermined distance from the upper peripheral rim of the cup.

3. In combination, a cup having a bottom wall and a cylindrical vertical wall terminating in an upper rim portion, a thin flexible member having a smooth outer periphery devoid of notches disposed within said cup, spaced stop means rigid with the vertical wall of the cup to removably maintain said member in a predetermined plane, certain of said stop means being engageable above said member, and others being engageable below said member, the outside diameter of said member being greater than the shortest diametrical

distance between opposed stop means whereby said member must be flexed in order to engage or remove it from engagement with said stop means.

4. A flow control member for use within a cup having holding means on the inner wall thereof a predetermined distance below its upper edge, comprising a thin, flat, flexible disc-like member having a diameter slightly less than the inside diameter of the cup so that there will be a narrow opening between the periphery of the member and the inner wall of the cup when it is disposed therein, said disc-like member having a handle to facilitate its insertion into and removal from the cup, said handle comprising a lateral bight portion on the outside of said flexible member, legs attached thereto slidably with respect to said flexible member, said legs being attached to heads on the side of the flexible member opposed to said bight portion of the handle, said heads acting as stop members and being movable to a position adjacent the flexible member, said handle facilitating the insertion and removal of the resilient member in the cup by serving as a fulcrum support when the circumferential edges of the flexible member are deflected.

5. A flow restricting device for a cup comprising a removable thin, resilient, metallic member to restrict the flow of liquid and means to maintain said member at a predetermined elevation relative to the upper peripheral edge of the cup, said means comprising a first set of diametrically opposed abutment members each having a flat bottom surface, and a second set of diametrically opposed abutment members each having a flat top surface, each of said abutment members being rigidly secured to an inner cylindrical wall surface in said cup with the flat surfaces of each set parallel and located a predetermined distance from the upper peripheral rim of the cup, said inner cylindrical wall surface being the inside of a ring member having a beaded upper rim portion and adapted to be removably press-fitted into said cup.
